UNITED STATES PATENT OFFICE

RUDOLPH BECKER, OF NORTH PLAINFIELD, NEW JERSEY, ASSIGNOR TO THE SINGER MANUFACTURING COMPANY, OF ELIZABETH, NEW JERSEY, A CORPORATION OF NEW JERSEY

MULTIPLE-THREAD TENSION-RELEASE MECHANISM

Application filed June 22, 1927. Serial No. 200,594.

This invention relates to multiple needle sewing machines and has for an object to provide a multiple thread tension release mechanism for such machines which is simple in construction and easy to assemble and operate, and which is unlikely to get out of order. In the preferred form of the invention, a plurality of tension devices of standard construction are mounted on one of three flat plates 5 preferably of the same size and shape. The tension-carrying plate is carried by four corner-posts or studs secured to a second of said plates, which may be called the base-plate; the tension-carrying plate and base-plate being thus held in spaced parallel relation. The base-plate is secured to a bracket mounted on top of the sewing machine gooseneck. Slidably mounted on the corner-posts, between the tension-carrying plate and base-plate, is 10 the third or movable plate which is shifted toward and away from the tension devices by a cam-mechanism actuated by a rock-shaft connected to the presser-foot lifter.

In the accompanying drawings Fig. 1 is a 15 rear side elevation of a sewing machine gooseneck embodying the invention. Fig. 2 is a top plan view. Fig. 3 is a transverse vertical sectional view. Fig. 4 is a perspective view of the movable tension-releasing plate and Fig. 5 is a perspective view of the actuating cam.

The invention is shown as embodied in a 20 sewing machine having a gooseneck 1, to which is pivoted at 2 the usual lifting lever 3 for the presser-foot 3'. Mounted on top of the gooseneck 1 is the bracket 4 in which is 25 journaled the rock-shaft 5 actuated by the crank-arm 6 connected by a link 7 to the rear end 8 of the presser-lifting lever 3. Secured to the bracket 4 is a rectangular base-plate 9 through which the rock-shaft 5 extends; such 30 rock-shaft being formed with a circular head 10 having a cylindrical flange 11 notched at diametrically opposed points to form cam-inclines 12. Fixed to the corners of the base-plate 9 are posts 13 which carry a tension-supporting plate 14 of the same size and shape as the base-plate 9. The plate 14 has mounted thereon a plurality of tension devices of standard form including the usual tension 35 disks 15 and tension release pins 16. Slidably

mounted on the posts 13 is a movable plate 17 having secured to its face adjacent the base-plate 9 a cam-disk 18 formed with diametrically opposed cam-follower lugs 19 having inclined edges 20 matching the cam-inclines 12. 40 A bow-spring 21 secured at 22 to the plate 14 urges the movable plate 17 toward the base-plate 9 and maintains the cam-follower constantly in engagement with the actuating cam member on the rock-shaft 5. The entire device is removable from and replaceable upon the gooseneck 1 as a unitary assembly, being held thereon by the screw 23. The invention is not to be understood as limited to the details of construction of the preferred embodiment illustrated as it is obviously susceptible of embodiment in various specifically different forms within the scope of the invention 45 defined by the appended claims.

Having thus set forth the nature of the invention, what I claim herein is:—

1. A multiple - thread tension - release mechanism comprising three plates disposed in spaced parallel relation, a plurality of posts fixed to the two outer plates and holding them separated and relatively fixed, the intermediate plate being slidably mounted on said posts, a plurality of tension devices mounted on one of said fixed plates and having tension release pins extending through the latter, and means for shifting the movable plate toward the tension release pins. 75

2. A multiple - thread tension - release mechanism comprising three plates disposed in spaced parallel relation, a plurality of posts for holding the two outer plates relatively fixed, the intermediate plate being movably mounted relative to said outer plates, a plurality of tension devices mounted on one of said outer plates and having tension-release pins extending through the latter, a rock-shaft extending through the other of said outer plates, and cam means on said rock-shaft for shifting the movable plate to actuate said tension-release pins. 80

3. A multiple - thread tension - release mechanism comprising a base-plate, a tension-supporting plate carried by the base-plate in spaced relation with the latter, a movable plate intermediate said base-plate 90

and tension-supporting plate, a cam-follower on said movable plate, a plurality of tension-devices mounted on the tension-supporting plate and including release pins extending through the tension-supporting plate and adapted to be simultaneously engaged by the movable intermediate plate, a rock-shaft transverse to and extending through said base-plate, and a cam-device on said rock-shaft cooperatively related to said cam-follower for moving the intermediate plate.

4. A multiple-thread tension-release mechanism comprising a base-plate, a tension-supporting plate carried by the base-plate in spaced relation with the latter, an intermediate movable tension-release plate, cam-follower lugs on said tension-release plate, a plurality of tension-devices mounted on the tension-supporting plate and including release pins extending through the tension-supporting plate and adapted to be simultaneously engaged by the movable intermediate plate, a rock-shaft transverse to and extending through said base-plate, and a cam-device on said rock-shaft in the form of a circular head having a cylindrical flange formed with notches defining cam-inclines which are cooperatively related to said cam-follower lugs for moving the intermediate plate.

In testimony whereof, I have signed my name to this specification.

RUDOLPH BECKER.
